(57) **CLAIM**

The ornamental design for a pet stroller, as shown and described.

DESCRIPTION

FIG. 1 is a perspective view of a pet stroller showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof;

FIG. 9 is a rear perspective view thereof, showing a first reduced compartment size;

FIG. 10 is a rear perspective view thereof, showing a second reduced compartment size;

FIG. 11 is a front perspective view thereof, showing an open canopy;

FIG. 12 is a front perspective view thereof, showing a bowl support in open position; and,

FIG. 13 is a front perspective view thereof, showing a bowl supported by the bowl support when in use.

The broken lines in FIG. 13 illustrate environment subject matter that forms no part of the claimed design.
